UNITED STATES PATENT OFFICE.

ROBERT J. MONTGOMERY, OF CHICAGO, ILLINOIS.

HAIR-BRUSH.

SPECIFICATION forming part of Letters Patent No. 674,121, dated May 14, 1901.

Application filed November 22, 1898. serial No. 697,170. (No model.)

To all whom it may concern:

Be it known that I, ROBERT J. MONTGOMERY, of Chicago, in the county of Cook and State of Illinois, have invented new and useful Improvements in Hair-Brushes, of which the following is a full, clear, and exact description.

This invention relates to hair-brushes in which the bristles are attached to a skeleton 10 or open-work bristle-frame formed separate from the back of the brush and removably attached to the same, the back of the brush having a concave or dish-like form, so as to provide an open space back of the bristle frame through which air and water may freely circulate either during the use of the brush or when it is desired to clean the same.

This specification is the disclosure of one form of my invention, while the claims define 20 the actual scope thereof.

Reference is to be had to the accompanying drawings, forming a part of this specification, in which similar characters of reference indicate corresponding parts in all the views.

25 Figure 1 is a longitudinal sectional view of the brush. Fig. 2 is a plan view of the brush with the bristles in section on the line 2 2 in Fig. 1. Fig. 3 is a transverse sectional view on the line 3 3 in Fig. 2. Fig. 4 is an enlarged 30 fragmentary end view of the bristle-frame with parts in section on the line 4 4 in Fig. 5, and Fig. 5 is a cross-section on the line 5 5 in Fig. 4.

The back of the brush has a handle 6 and 35 the body portion or back proper, 7, the latter having its inner face formed with a concavity or dish-shaped recess 8. At the outer extremity of the body or back proper a lug 9 is rigidly attached and engages with one end of 40 the bristle-frame to assist in holding the bristle-frame in place. The other end of the bristle-frame is held by a dog 10, pivoted to the handle 6, opposite the lug 9, and pressed on by a spring 11, suitably mounted in said 45 handle.

The bristle-frame is formed of an integral mass of vulcanized rubber or like non-corrosive substance and comprises a series of concentric oval-shaped channels 12, rigidly joined 50 to each other by bridge-pieces 14, as shown best in Fig. 2. The channels 12 are open at their inner sides—that is to say, the sides ad-

jacent to the back of the brush—and are provided at their outer sides with openings 15, (see Fig. 4,) surrounded by bosses 16. Through 55 these openings and bosses are passed the tufts 17 of bristles, which are lapped around a wire 18, passing through such channel, the looped or middle portions of the bristles passing around the wires, while the end portions of 60 the bristles are projected outward to form the rubbing-surface of the brush. When the bristles and wires are so arranged within the several channels, the channels are filled with a waterproof cement or packing 18^a, which 65 is molded up in the form of an arch across each channel, so that the bristle-frame when finished is formed of approximately round members, as shown in Figs. 3 and 5.

A brush thus constructed will be very durable and at the same time may be cleaned and kept clean very effectively. The bristle-frame may be frequently removed from the back for the purpose of cleaning or for repair, or, if desired, a number of bristle-frames of different kinds may be supplied with a single back and interchanged at will. The bristles as secured in the frame are fastened so that it is impossible to pull them out or otherwise injure them, and since no water 80 or other moisture may penetrate to the interior of the channels there is no possibility of the bristles rotting at their bases.

Various changes in the form, proportions, and minor details of my invention may be resorted to without departing from the spirit and scope thereof. Hence I do not consider myself limited to the exact construction herein shown, but believe that I am entitled to all such variations as come within the scope 90 of my claims.

Having thus described my invention, I claim as new and desire to secure by Letters Patent—

1. A bristle-frame for brushes constructed 95 with a series of channels joined to each other at intervals by integral arms, openings through the walls of the channels, bristles passing through said openings, and a waterproof filling laid in the channels to cover the 100 bristles.

2. A molded or cast skeleton bristle-holding frame, comprising a plurality of concentrically-arranged channels integrally connect-

ed, said channels having openings through their bottom walls and being provided with apertured bosses surrounding said openings, in combination with bristles and means for 5 securing bristles in said channels.

3. A bristle-holding frame constructed of a series of channels connected with each other by integral bridge-pieces, openings through the walls of said channels, a core-wire laid in 10 the channels, bristles passing around said core and extending through the openings in the channels.

4. A bristle-holding frame constructed of a series of channels connected with each other 15 by integral bridge-pieces opening through the walls of said channels, a core-wire laid in the channels, bristles passing around said core and extending through the openings in

the channels, and a waterproof filling laid in the channels to cover the core and the bristles. 20

5. A cast or molded bristle-frame comprising a plurality of channels secured together by integral arms, said channels having openings through the bottom walls thereof, and apertured bosses surrounding said openings, core-wires laid in the channels, bristles passing through said openings and having their bases tied to the core-wires, and a waterproof filling in the channels uniting the wires 25 and the bristles. 30

ROBERT J. MONTGOMERY.
